UNITED STATES PATENT OFFICE.

WILLIAM P. WITHEROW, OF PITTSBURGH, PENNSYLVANIA, ASSIGNOR, BY MESNE ASSIGNMENTS, TO COLONIAL TRUST COMPANY, TRUSTEE, OF PITTSBURGH, PENNSYLVANIA, A CORPORATION OF PENNSYLVANIA.

ARTICLE OF MANUFACTURE AND METHOD OF MAKING THE SAME.

Application filed February 14, 1925. Serial No. 9,140.

The present invention relates broadly to the art of metal working, and more particularly to the art as applicable to the production of articles required to have a hard, uniform wearing surface, such as gears, cams, shafts and the like, although the utility of the invention is not limited in this respect.

At the present time it is customary to produce articles of the general character herein contemplated by providing a blank having an amount of metal sufficient to form the desired article. This blank is then either upset to effect a preliminary distortion of its mass such as to facilitate subsequent operations, or it is drawn down under a hammer for the same purpose. Thereafter, the article is produced from the roughly shaped blank by suitable machining operations. The machined article is then treated, as by case hardening, to give the desired hardness and wearing qualities.

Actual tests, such as the so-called hardness test, are then relied upon to determine whether these hardened articles will pass inspection. It frequently happens that the tests show non-uniformity as to hardness in different parts of the same article, the variations being such that quite often the article has to be rejected. This is particularly true in the case of gears, when one tooth, or certain teeth, are so soft as to render the whole gear unfit for satisfactory service.

It also frequently happens that the case hardening penetrates unequally at different portions of a tooth. In the event of excessive penetration on opposite sides of a tooth, the interior tooth structure relied upon for carrying the load is weakened to such an extent that the tooth may easily be broken off. It is apparent, therefore, that uniform hardness of a tooth particularly, is extremely desirable.

I have found that this non-uniformity is to a large extent, at least, attributable to the original shaping operations on the blank. In the case either of upsetting or hammer shaping, the original fiber arrangement is irregularly and non-uniformly distorted. This results in the production of an article having no predetermined or uniform fiber disposition. In case hardening, the degree of hardness varies directly as the disposition of fiber

varies, thereby indicating the desirability of a shaping process capable of effecting a predetermined disposition of the fiber. 55

It is an object of the present invention to improve articles of the character herein contemplated, and by uniform fiber disposition to reduce to a minimum variations in hardness in different parts of the same article or 60 in successive articles.

In the accompanying drawings there is shown for purposes of illustration only, a preferred embodiment of the present invention, it being understood that the drawings 65 do not define the limits of my invention, as changes in the construction and operation therein disclosed may be made without departing either from the spirit of the invention or the scope of my broader claims. It 70 will be further understood that the invention is not limited to the sequence of steps herein-after set out.

In the drawings:

Figure 1 is a side elevation of a die rolled 75 blank particularly adapted for the production of a pinion shaft and gear, the general outline of the finished shaft and gear being indicated in dotted lines;

Figure 2 is a longitudinal sectional view 80 through the blank shown in Figure 1, for the purpose of illustrating the disposition of the fibers effected by the die rolling operation.

In carrying out the present invention I select a leader having dimensions suitable for 85 the production of the desired blank. In the case of blanks having a substantially circular cross section throughout the major portion of their lengths, I preferably utilize a leader having a major and a minor axis. In the 90 illustrated embodiment of my invention, the leader is subjected to a die rolling operation in a pair of rolls having matrix portions adapted to form successive pairs of blanks attached in end to end relationship. After 95 the die rolling operation the blanks may be separated in any desired manner to provide pairs as illustrated in the drawings.

Each blank preferably comprises a shaft forming portion 2, having a length and diameter suitable for the formation of the finished shaft, and an enlarged head 3 having dimensions suitable for the production of a gear. 100 In actual practice the matrix portions of the

grooves are preferably so shaped that alternate blanks extend in opposite directions. By such an arrangement, the heads 3 of comparatively large diameter occupy adjacent 5 relationship, thereby facilitating the work of the rolls and tending to eliminate abrupt changes of section such as would be necessary if successive blanks extended in the same direction. The action of the rolls on the leader 10 is such as not to objectionably or non-uniformly destroy the longitudinal arrangement or disposition of the fibers. By actual tests it has been found that the fibers tend to follow the general contour of the blanks, extending continuously and substantially uniformly 15 from end to end of the blanks. This uniformity is highly desirable as will hereinafter be more fully pointed out.

After the blanks have been separated into 20 pairs or units in any desired manner, they may be subjected to suitable finishing operations, either in pairs or by units, to reduce the same to the desired dimensions. Conveniently, this may be accomplished by subjecting the blanks in pairs to suitable finishing 25 or machining operations in a lathe or other form of apparatus. After the blanks have been reduced to finished dimensions, the teeth may be formed thereon in any desired 30 manner. It will be apparent, however, that the machining or finishing operations will not have any effect upon the fiber disposition, so that the uniformity in the arrangement or disposition of the fibers will be maintained 35 in the finished articles.

Dimensions of articles of the character herein contemplated are so figured as to provide an ample safety factor. It is essential, however, to provide extremely hard and uniform 40 wearing surfaces. Such wearing surfaces are ordinarily produced by case hardening to effect the formation of a case of the desired thickness. I have found that with articles having non-uniform fiber arrangements, the case hardening is extremely irregular tending to penetrate to greater depth at certain portions than at other portions. It will be obvious that this results in the 45 production of gears having one or more teeth liable to chip or break off in service. These objections are entirely obviated by the present invention, by reason of the uniform fiber disposition effected by the die rolling operation, thereby insuring a uniform case hardening 50 throughout the entire body of the article,

the case being of uniform depth throughout, with consequent uniformity of strength.

The advantages of the present invention arise from the provision of an article of manufacture having uniform wearing qualities 60 and uniform strength throughout, by reason of the preliminary shaping of the blanks in such manner as to insure uniform fiber disposition through the entire body of the blank.

Further advantages of the invention arise 65 from the method of producing articles of the character herein contemplated, the die rolling not only insuring the desired uniformity, but also producing such articles on a much greater scale than can possibly be obtained by either upsetting or hammer drawing.

While I have specifically referred herein 70 to gears, and to case hardening, it will be apparent from a consideration of the invention, specification and claims that the invention is not limited to any particular article, it being applicable, generally, to shafts, gears, 75 axles and the like, whether case hardened or hardened by some other method, such as 80 heat treating or otherwise. I therefore use the term "articles" in its generic sense as including the range of articles to which the invention is applicable, and the term "hardening" also as a generic expression definitive of 85 an operation to accomplish the desired result rather than any specific operation.

I claim:

1. In the method of producing a pinion shaft and gear, the steps consisting in die 90 rolling a leader to produce a blank following the general contour of the finished article and in which the fibre is substantially symmetrically disposed with reference to the axis of the pinion shaft and gear, working on the blank 95 to reduce it to substantially finished dimensions, and hardening the shaped blank.

2. As an article of manufacture, a pair of blanks for the production of pinion shafts and gears, said blanks each having enlarged 100 portions for the formation of the gear, the blanks being arranged in end to end relationship with the enlarged portions adjacent one another, the pair of blanks having a fibre disposition which is substantially symmetrical 105 with respect to the axis of the blanks.

In testimony whereof I have hereunto set my hand.

WILLIAM P. WITHEROW.
